(57) **CLAIM**

The ornamental design for a wrist brace, as shown and described.

DESCRIPTION

FIG. 1 is a top view of the inside surface of the wrist brace, showing our new design.

FIG. 2 is a top view of the outside surface thereof.

FIG. 3 is a view thereof, from the outside in use condition; and,

FIG. 4 is a view thereof, from the palm side in use condition. The broken line showing of the hand in FIGS. 3 and 4 is for illustrative purposes only and forms no part of the claimed design.
